APPARATUS FOR FORMING POINTED CORNERS

Edward B. Roby, New York, N. Y., assignor to
The S and R Folding Machine Co. Inc., New
York, N. Y., a corporation of New York

Application August 31, 1932. Serial No. 631,232

14 Claims. (Cl. 223—55)

This invention relates to an apparatus for forming pointed corners in garments, such as collars.

Objects

Among the principal objects which the present invention has in view are:—To provide an apparatus having means wherein the corners of collars will be made permanently flat and pointed; to provide an apparatus having means whereby the two corners of a collar will be shaped and pointed simultaneously; to employ both heat and pressure and effect a shaping of the product during the application of the heat and pressure; to provide an apparatus which will perform the shaping of a collar having a uniform thickness throughout; to secure simplicity of construction and operation; and to obtain other advantages and results as may be brought out in the following description.

Drawings

Figure 1 is an elevation of an apparatus embodying my invention;

Figure 2 is a plan of the shaping die and operating means therefor with a collar in position therein;

Figure 3 is a sectional elevation of the pressure means employed;

Figure 4 is a sectional view as taken on line 4—4 of Figure 3;

Figure 5 is a cross-section through the plunger showing the pressure die therebelow;

Figure 6 is a perspective of the shaping means with a portion of a collar therein;

Figure 7 is a sectional view shown as taken on line 7—7 of Figure 2;

Figure 8 is a similar view in different operative position; and

Figure 9 is a face view of a collar with the corner pointed by use of the present invention.

Description

As seen in the drawings, the reference numeral 15 indicates my improved apparatus having a base 16, and a standard 17 terminating in a head 18 providing a vertical slideway for a plunger 19. The standard 17 furthermore provides a bed 20 positioned below and away from the plunger and adapted to support a forming die 21. The plunger 19 carries a pressure die 22 and a creasing blade 23 and the parts are arranged with the pressure die and creasing blade overlying a portion of the forming die and adapted to be brought down upon the same.

As here shown, operation of the pressure die 22 and creasing blade 23 is obtained by means of a treadle 24 connected by a link 25 to a first class lever 26, an intermediate part of which engages the upper end of the plunger 19. Link 25 attaches to one end of this lever 26, whereas the other end is fulcrumed as at 27 in a bracket 28 forming part of the head of the apparatus.

Preferably lever 26 provides a long arm between the plunger 19 and the connection of the link 25, and provides a short arm between the plunger and the fulcrum 27, so that a moderate pressure exerted by the operator may apply a considerable pressure to the plunger and the pressure die 22 and the creasing blade 23.

The forming die comprises in the present showing a fixed member 29 and a transversely movable member 30, these parts being so arranged and associated as to permit one edge of the collar 31 to engage an edge or abutment of the fixed member 29, and the other edge of the collar to engage an edge or abutment of the movable member 30.

As seen in the present showing, the fixed member 29 of the forming die is cut away as at 32 to receive the unfolded selvage or marginal end edge 33 of the collar 31 as well as the extreme bent-in end or tip 34 which may be called the reinforced corner of selvage 33. This tip is a triangular piece of the goods aligned with the line of folding of the margin or hem of the collar.

The movable die member 30 preferably provides a surface upon which the collar 31 may be placed flatwise in addition to engagement against the abutment above referred to.

The pressure die 22 is preferably shaped to conform with the desired collar corner surface of the collar 31 without engaging the raised portions of the forming die providing the abutments for shaping the collar.

Suitable means are provided for retracting or drawing the movable member 30 away from the fixed member 29 as the pressure die 22 is lowered. Said means in this instance may conveniently comprise the lowering of the creasing blade 23 simultaneously with the pressure die and forcing said blade between the dies. Said pressure die and creasing blade are preferably carried by the plunger 19 by being attached thereupon as by a pair of threaded nuts 35, the lower portion of the plunger being screw-threaded to receive the same as clearly shown in Figure 4.

The pressure die 22 is suitably attached to the plunger, as by a stud 36 fitted within the plunger, there being a coil spring 37 within the plunger at the upper end of the stud. Said stud 5 may have a keyway 38 to receive a pin 39 which extends laterally thereinto through the lower extremity of the plunger. The keyway is closed at its ends thereby limiting the movement of the stud and retaining the stud within the 10 plunger.

As the plunger is being lowered, the creasing blade 23 moves downward and engages the fold line of the collar 31 and then passes downwardly between the fixed member 29 and the movable member 30 (see Figures 7 and 8). The pressure die 22 simultaneously engages the flat surface of the collar. As the creasing blade is passing downwardly between the fixed member and the movable member, the movable member 20 moves outwardly and away from the fixed member.

A bracket 40 is attached to the movable member 30 and extends transverse to the direction of movement of said member so as to rest 25 against the bed 20 when the die members are as close together as they should be.

Said bracket has an opening 41 to permit a stud 42 to pass therethrough, said stud being secured to the bed.

30 At the outer end of the stud is a collar 43 against which one end of a heavy coil spring 44 rests, the other end of said spring bearing against the bracket 40.

When the corner of the collar 31 has been 35 properly shaped and pointed, the plunger 19 is permitted to rise, thereby releasing the creasing blade 23 from between the fixed member 29 and the movable member 30, and simultaneously the pressure exerted by the spring 44 against the bracket 40 will cause the movable member to return to normal position until the 40 next operation.

Means are provided in the movable die member 30 to limit the outward movement of said member, and in this instance I have shown a 45 pair of pins "30a" mounted in the bed 20 and extending upwardly through slotted portions "30b" in the die member.

It is to be noted that to insure proper smoothing and creasing, introduction of heat is made 50 to the collar 31 being operated on by a heater element 45 (diagrammatically shown in Figure 1) attached to the under side of the bed 20 in proper association with the forming and pressure dies and the creasing blade.

As seen in Figure 9, I have illustrated the 55 collar 31 in its final condition before rows of stitches (not shown) are applied to the marginal edges. It is likewise to be understood that this collar is of a single thickness, and that the two corners have been properly shaped and pointed simultaneously and in one operation.

I claim:

1. An apparatus as characterized comprising in combination, a forming die having an abutment for engagement by a formed edge of a garment, said abutment having a recess for receiving an unformed portion of the edge of said garment, and means for forming said unformed portion and adapted to remove said formed portion from the recess.

2. An apparatus as characterized comprising in combination, a forming die having an abutment for engagement by a formed edge of a garment, said abutment having a recess for

receiving an unformed portion of the edge of said garment, and means for creasing said unformed portion and adapted to remove said creased portion from the recess.

3. An apparatus as characterized comprising 80 in combination, a forming die having an abutment for engagement by a formed edge of a garment, said abutment having a recess for receiving an unformed portion of the edge of said garment, and a creasing blade for creasing said unformed portion and adapted to remove said creased portion from the recess.

4. An apparatus as characterized comprising 85 in combination, a forming die having an abutment for engagement by a formed edge of a garment, said abutment having a recess for receiving an unformed portion of the edge of said garment, a creasing blade for creasing said unformed portion and adapted to remove said creased portion from said recess, and a yielding 90 means at the opposite side of said blade from the recess for deferring movement of the garment on that side of the blade and leaving the portion of the garment on the other side of the blade free to be actuated by the blade.

5. An apparatus as characterized comprising 95 in combination, a fixed forming die member having an abutment for engagement by an edge of a garment, a movable die member adjacent the first die member adapted to receive the 100 garment thereupon, and movable means for simultaneously spreading said die members and forcing the garment between said die members.

6. An apparatus as characterized comprising 110 in combination, a fixed forming die member having an abutment for engagement by an edge of a garment, a movable die member adjacent the first die member adapted to receive the 115 garment thereupon, a movable blade for simultaneously spreading said die members and forming the garment, and means for pressing the movable die member normally toward the fixed die member.

7. An apparatus as characterized comprising 120 in combination, a fixed forming die member having an abutment for engagement by an edge of a garment, a movable die member adjacent the first die member adapted to receive the 125 garment thereupon, a movable blade for simultaneously spreading said die members and forcing the garment between the said die members, and means for pressing the movable die member normally toward the fixed die member.

8. An apparatus as characterized comprising 130 in combination, a fixed forming die member having an abutment for engagement by an edge of a garment, a movable die member adjacent the first die member adapted to receive the 135 garment thereupon, a movable blade for simultaneously spreading said die members and forming the garment, means for pressing the movable die member normally toward the fixed die member, and a stop for retaining said die members separated sufficiently to enable the said movable blade to be forced therebetween.

9. An apparatus as characterized comprising 140 in combination, a fixed forming die member having an abutment for engagement by an edge of a garment, a movable die member adjacent the first die member adapted to receive the 145 garment thereupon, a movable blade for simultaneously spreading said die members and forcing the garment between the said die members, means for pressing the movable die member normally toward the fixed die member, and a stop 150

for retaining said die members separated sufficiently to enable said movable blade to be forced therebetween.

10. An apparatus as characterized comprising 5 in combination, a forming die member having an abutment for engagement by a formed edge of a garment, said abutment having a recess for receiving an unformed portion of the edge of the garment, a movable die member adjacent the first said die member and adapted to receive thereupon the portion of the garment adjacent said unformed portion, and means for simultaneously spreading said die members apart and forcing the said unformed portion of the 15 garment therebetween.

11. An apparatus as characterized comprising in combination, a forming die member having an abutment for engagement by a formed edge of a garment, said abutment having a 20 recess for receiving an unformed portion of the edge of the garment, a movable die member adjacent the first said die member and adapted to receive thereupon the portion of the garment adjacent said unformed portion, means for simultaneously spreading said die members apart 25 and forcing the said unformed portion of the garment therebetween, and means for pressing the movable die member normally toward the fixed die member.

12. An apparatus as characterized comprising 30 in combination, a forming die member having an abutment for engagement by a formed edge of a garment, said abutment having a recess for receiving an unformed portion of the edge of the garment, a movable die member adjacent the first said die member and adapted to receive thereupon the portion of the garment adjacent said unformed portion, means for simultaneously spreading said die members apart 35 and forcing the said unformed portion of the garment therebetween, means for pressing the movable die member normally toward the fixed die member, and a stop for retaining said die members separated sufficiently to enable the said 40 spreading means to be forced therebetween.

13. An apparatus as characterized comprising in combination, a forming die member having an abutment for engagement by a formed edge of a garment, said abutment having a recess for receiving an unformed portion of the edge of the garment, a movable die member adjacent the first said die member and adapted to receive thereupon the portion of the garment adjacent said unformed portion, a creasing blade for simultaneously spreading said die members apart and forcing the said unformed portion of the garment therebetween, means for resiliently pressing the movable die member toward the other die member, and a stop for retaining said die members separated at least substantially the thickness of said creasing blade to enable said blade to be forced between the die members and carry the unformed portion of the garment therewith between said die members. 80 85 90

14. An apparatus as characterized comprising in combination, a forming die member having an abutment for engagement by a formed edge of a garment, said abutment having a recess for receiving an unformed portion of the edge of the garment, a movable die member adjacent the first said die member and adapted to receive thereupon the portion of the garment adjacent said unformed portion, a creasing blade for simultaneously spreading said die members apart and forcing the said unformed portion of the garment therebetween, means for resiliently pressing the movable die member toward the other die member, a stop for retaining said die members separated at least substantially the thickness of said creasing blade to enable said blade to be forced between the die members and carry the unformed portion of the garment therewith between said die members, and yielding means as the opposite side of the blade from the recess for holding the garment on that side of the blade and leaving the portion of the garment on the other side of the blade free to be actuated by the blade. 100 105 110 115 120 125
